Primary Examiner — Robin V Webster*(74) Attorney, Agent, or Firm* — Michael Best & Friedrich LLP(57) **CLAIM**

We claim the ornamental design for a shower faceplate, as shown and described.

DESCRIPTION

FIG. 1 is a front perspective view of a shower faceplate having a transparent or translucent front.

FIG. 2 is a front view of the shower faceplate shown in FIG. 1.

FIG. 3 is a rear perspective view of the shower faceplate shown in FIG. 1.

FIG. 4 is a rear view of the shower faceplate shown in FIG. 1; and,

FIG. 5 is a right side view of the shower faceplate shown in FIG. 1, the left side, top and bottom views being substantially the same.

1 Claim, 3 Drawing Sheets(56)
